CLINKER GRINDER

Donald J. Mosshart, Springfield, Pa., assignor to
Westinghouse Electric & Manufacturing Com-
pany, East Pittsburgh, Pa., a corporation of
Pennsylvania

Application August 16, 1933, Serial No. 685,435

7 Claims. (Cl. 83—12)

My invention relates to combustion apparatus and more particularly to improvements in the means for crushing or grinding the ash and clinker coming from furnaces using solid fuels.

5 In apparatus of this character heretofore known to me, it is customary to provide a pit or receptacle, into the upper end of which is deposited ash and clinker discharged from the furnace. The upper end of the pit may be in direct communication with the furnace, or it may be positioned to receive the ashes from a dump grate, the end of a chain grate or in fact any type of fuel burning equipment. Usually, the ash and clinker are supported in the pit by one or more 10 grinder rolls disposed in the lower portion thereof which, when rotated, also act to reduce the ash and clinker to relatively small particles and remove it from the furnace. The purpose of this 15 type of grinding apparatus is to reduce the ash and clinker to particles small enough to permit its being handled by modern ash-removing apparatus.

In the installations where the upper portion of the pit is in direct communication with the furnace, the grinder rolls are so operated as to maintain a substantial head of ash in the pit which serves to prevent atmospheric air from entering the furnace from beneath the rolls and adversely affecting combustion in the furnace.

30 Prior apparatus of this character may be divided into two types: first, those wherein a roll having radial teeth thereon, and a stationary plate are disposed in spaced relation and the roll is rotated toward the stationary plate to grind 35 the clinker and ash therebetween and discharge the ground material from the pit; and second, those wherein one or more pairs of rolls also having radial teeth are arranged in closely spaced relation with their axes parallel and the rolls 40 forming a pair are rotated toward one another, whereby the clinker and ash is ground therebetween and the ground material discharged from the pit.

45 In the first type, the clinker is fed into the space between the plate and the roll, by virtue of the action of the teeth. The teeth grip the clinker and draw it into the grinding zone and break it up against the stationary plate and discharge the broken clinker from the pit. In this 50 type, it is necessary for proper feeding of the clinker to the grinding zone to provide a relatively large space between the roll and the stationary plate. If the space is too small, large clinkers cannot be firmly gripped by the teeth and hence 55 will slip upward into the pit instead of being

wedged down into the space and ground by the coaction of the teeth and plate.

In the second type, the clinker is positively gripped from both sides by the teeth and is thereby more effectively wedged down into the space 5 between the rolls. In this type, the clinker is ground up more by compression or crushing action of the rolls than by a tooth action.

The size of the space between the roll and plate of the first type and the size of the space between the rolls forming a pair of the second type determine in each case the size of the ground particles. As the coating rolls forming each pair of the second type positively grip the clinker from both sides, it is obvious that a smaller space 10 between the grinding surface is required and hence a finer ash can be produced by this type than by the first type. Also, the crushing action of the two rolls results in a finer ash. However, in cases where the ground ash can be sold for 15 useful purposes, for example, in road building, as a filler for certain types of concrete or for ballast; neither of the above-described types can practically produce an ash which is sufficiently fine to meet the requirements. Heretofore, when 20 such a market was found for the ash, the ash would have to be again ground by additional equipment or be crushed further manually.

An object of the present invention is to provide 30 an improved form of grinding mechanism which can be disposed in the lower portion of the conventional type of ash pit or receptacle which will operate as effectively and efficiently as the prior 35 types of apparatus and which at the same time will grind or crush the ash and clinker to a sufficiently fine degree to permit its being sold for uses such as are named above, without the necessity of further grinding.

In accordance with a specific embodiment of 40 my invention, I attain the above objects by providing a grinding mechanism of the second type referred to above wherein a third grinder roll is disposed below the customary pair of grinder rolls and is capable of being moved back and forth about its axis either by virtue of its frictional contact with the streams of ash moved by the other two rolls, or if preferred may be positively oscillated by mechanical means. By reason of this construction, the ash is first ground as in prior apparatus, by the coaction of the pair of 45 rolls and is further ground to a finer degree by the coaction of each roll of the pair with the third roll disposed therebelow.

These and other objects are effected by my invention, as will be apparent from the following 55

description and claims taken in accordance with the accompanying drawings, forming a part of this application, in which:

Fig. 1 is a transverse vertical section through a clinker pit showing my improvement as applied thereto, the section being taken on the line I—I of Fig. 2 and on a larger scale than Fig. 2;

Fig. 2 is a horizontal fragmentary section taken on the line II—II of Fig. 1, certain parts being broken away to illustrate more clearly the present invention;

Fig. 3 is a vertical fragmentary section taken on the line III—III of Fig. 2;

Fig. 4 is a fragmentary detail view on the same scale as Fig. 1 illustrating, in end elevation, the driving mechanism for the grinder rolls;

Fig. 5 is an enlarged fragmentary vertical section taken on the line V—V of Fig. 2, and illustrating an intermediate bearing support for the grinder rolls;

Fig. 6 is an enlarged fragmentary vertical section taken on the line VI—VI of Fig. 2, and illustrating an end bearing support for the grinder rolls;

Fig. 7 is a fragmentary detail sectional view taken on the line VII—VII of Fig. 3, and illustrating the construction of the third grinder roll;

Fig. 8 is a fragmentary detail sectional view taken on the line VIII—VIII of Fig. 5, and illustrating the manner of securing the ends of the shafts for the third grinder roll to the intermediate bearings;

Fig. 9 is a fragmentary detail sectional view taken on the line IX—IX of Fig. 6, and illustrating the manner in which the shaft of the third grinder roll is secured to the end bearings.

Fig. 10 is a fragmentary sectional view similar to Fig. 3 and illustrating a modified form of construction wherein the third roll is mechanically oscillated; and

Fig. 11 is a view similar to Fig. 4 and showing the driving mechanism for the rolls shown in Fig. 10.

Referring now in detail to the construction illustrated, in Figs. 1 to 9 inclusive, it will be observed that I have shown my invention as applied to a stoker-fired boiler furnace, a portion of which is indicated by the reference numerals 10 in Fig. 1. The reference numeral 11 indicates the lower portion of a stoker grate which serves to support the fuel during combustion in a manner well understood by those skilled in the art. The reference numeral 12 indicates a clinker pit which is disposed transversely of the lower discharge end of the stoker 11 and receives the ash and clinker as it is discharged.

The clinker pit 12 comprises end walls 13 and 14, respectively, a front wall 15 and a rear wall 16. The ash and clinker is supported within the pit 12 by an ash grinding and removing apparatus indicated in its entirety by the reference numeral 17. The apparatus 17 discharges the ash from the lower portion of the pit 12 and into the upper portion of an ash storage pit 18, from which the ash may be periodically removed by any suitable ash-removing apparatus (not shown).

The apparatus 17 comprises a pair of rolls 19 and 20 disposed longitudinally of the pit 12 with their axes arranged parallel to one another and in an approximately horizontal plane. The mechanism 17 also comprises a third roll 21 disposed beneath the rolls 19 and 20 and having its axis arranged parallel to and spaced an equal

distance from the respective axes of the rolls 19 and 20.

Each of the rolls 19 and 20 comprises a shaft portion 22 and a detachable grinding portion 23 having radially extending teeth 24 fixed thereon. For the major portion of the length of the shaft 22, it is square in cross-section as indicated in Figs. 2 and 3, but, at the ends thereof and at spaced intermediate points, the shaft portions are round to provide journals 25 (see Figs. 5 and 6), the purpose of which are to support the rolls for rotation about their respective axes.

The end journals 25 are disposed within end bearings 26 and 27 carried by bearing supports 28 and 29, respectively, the latter being supported within the end walls 13 and 14, respectively of the clinker pit. Intermediate journals 25 are carried by bearings 30 and 31, which are in turn supported respectively by intermediate bearing supports 32 and 33 disposed transversely of the lower portion of the pit 12 at intermediate points, the number of intermediate bearings provided depending upon the length of the pit.

In Fig. 6, the end bearings 27 and their support 29 are shown in side elevation. As the other end bearings 26 and support 28 are identical in construction with the bearings 27 and support 29, a description of the latter is believed to be sufficient. The bearings support 29 is disposed within a recess in the end wall 14 of the pit and is provided with the pair of bearings 27, 27 which, as stated, receive the journal portions 25 of the shafts of the rolls 19 and 20.

In Fig. 5, I have shown a side elevation of the intermediate bearing support 33 which is identical in construction with support 32. As shown, the intermediate bearing support 33 is secured at its outer ends by suitable bolts 34 to longitudinally extending I-beams 35 and 36 which also serve to support the pit walls. It will be observed that shims 37 are disposed beneath the bearing supports and the I-beams 35 and 36, the purpose of which is to provide for adjusting the position of the bearings and consequently the rolls 19 and 20 and 21 with respect to the walls of the pit 12.

The third roll 21 is composed of a plurality of sections 38, 39, and 40 (see Figs. 2 and 3), the end sections 38 and 40 extending from an end bearing support to the adjacent intermediate bearing support, and the section 39 between the two intermediate bearing supports. Each section comprises a cylindrical shaft or rod 41 fixed at its ends in the bearing supports and a plurality of annular rings 42 loosely mounted on the rod so as to be free to rotate about the rod 41 in either direction (see Fig. 7). The ends of each rod or shaft 41 are fixed to a block 43 by a locking pin 44, and the blocks are detachably held within recesses 45 in their respective bearing supports by plates 46 and bolts 47. Shims 48 are provided between the plates and blocks to provide for adjustment of the third roll 21 with respect to the rolls 19, 20 so as to vary the size of the particles passing between the third roll and either of the rolls 19 and 20. (See Figs. 5, 6, 8, and 9.)

As will be observed from examination of Figs. 2, 3, and 4, the ends of the rolls 19 and 20 extend through the end wall 14 of the pit 12 and are operated by a pawl and ratchet mechanism 49 disposed at the outside of the pit. The mechanism 49 comprises ratchet wheels 50 and 51 keyed to the shafts of the rolls 19 and 20, respectively. Yoke elements 52 and 53 are loosely mounted

upon the shafts and carry pivoted pawls 54 and 55 engaging respectively the ratchet wheels 50 and 51. The upper ends of the yokes 52 and 53 are connected by a link 56 and the yoke 53 is connected to an operating arm 57 which may be connected to any suitable source of power (not shown). As will be readily understood, oscillation of the yokes 52 and 53 by the arm 57 causes the pawls 54 and 55 to impart an intermittent 5 rotary movement to each of the shafts. The movement of the shafts will be toward each other. The rolls 19 and 20 are prevented from rotating in the opposite direction by means of pivoted catches 58 and 59, carried by the stationary 10 supporting structure and engaging the lower end of the ratchet wheels 50 and 51, respectively. The catches 58 and 59 are counterweighted, as indicated at 60, so as to maintain their engagement with their respective ratchet wheels.

15 In Figs. 10 and 11 I have illustrated a slightly modified form of construction wherein the third rod 21a, instead of being rotated by virtue of its frictional engagement with streams of ash moved downwardly by the pair of rolls as in the 20 previously described modification, is positively oscillated by mechanical means. To this end the roll 21a is provided with journals 70 which fit within bearings 71 and 72 provided in the intermediate and end bearing supports 32a and 29a respectively.

25 The roll 21a comprises a squared shaft portion 73 on which is fitted grinding sections 74. The roll 21a is provided with an end extension 75 which extends outside of the pit wall 14a and to which is fixed a lever 76. The lever 76 is connected by a link 77 with one arm 78 of a bell crank lever 79 fixed to an oscillating shaft 80 driven from any suitable source of power (not shown). Another arm 81 of the lever 79 is 30 connected by a link 82 with the yoke 53a. The link 82 imparts an intermittent rotary movement to the rolls 19a and 20a through the yoke 53a, link 56a, yoke 52a, pawls 54a and 55a and ratchet wheels 50a and 51a in the same manner as in 35 the previously described modification. Oscillatory movement is imparted to the roll 21a from the bell crank lever 79 by the arm 78, link 77 and lever arm 76. From the above, it will be seen that as the roll 19a is moved clockwise the roll 21a is moved counter-clockwise; and, as the roll 20a is moved counter-clockwise the roll 21a is moved clockwise.

40 From the above description, it will be readily seen that I have provided an extremely simple and rugged means for reducing the particles of ash and clinker to a very small size. The material in the pit is first ground by the coaction of the pair of rolls 19 and 20 of Figs. 1 to 9 inclusive or 19a and 20a of Figs. 10 and 11 and is further ground and to a very fine degree by the coaction of each of the pair of rolls with the third roll 21 or 21a, the spaces between each roll of the pair and the third roll being substantially less than the space between the rolls comprising the pair. As the third roll is capable of being oscillated in both directions which may be effected either by virtue of its frictional engagement with the ash propelled downward by the rolls 19 and 20 as disclosed in Figs. 1 to 9 inclusive or by virtue of the mechanical drive disclosed in Figs. 10 and 11; the same crushing action of the ash is had by the coaction of each of the rolls of the pair with the third roll 21 as is had in the initial crushing effected by the coaction of the rolls forming the pair.

45 While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

50 What I claim is:—

1. In a clinker grinder for combustion apparatus, cooperating members providing for a first stage of crushing of material passing therebetween and including a toothed roll and a roll having circumferential grooves for the teeth of the first stage crusher roll and cooperating with the latter to provide a second stage of crushing for material issuing from the first stage, said second stage crusher roll being spaced closer to the first stage roll than the spacing of the latter with respect to the other member of the first stage.

2. In a clinker grinder for combustion apparatus, cooperating members including a roll defining a first crushing stage for material passing therebetween and including a crusher roll cooperating with the first roll and spaced closer to the latter than the members of the first stage to define a second crushing stage for material issuing from the first stage, said second stage crusher roll embodying a shaft with a plurality of rings disposed in abutting, side-by-side relation thereon.

3. In a clinker grinder for combustion apparatus, cooperating members defining a first crushing stage for material passing therebetween and including a crusher roll having teeth and a crusher roll spaced closer to the first stage crusher roll than the members of the first stage and cooperating with the first roll to define a second crushing stage for material issuing from the first stage, said second crushing stage roll embodying a shaft with a plurality of rings disposed thereon in side-by-side relation and said rings having lateral spacing means so as to define circumferential grooves for the teeth of the first stage roll.

4. In a clinker grinder for combustion apparatus, first and second toothed rolls rotatable toward each other to effect a first stage of crushing for material passing therebetween and a third roll provided with circumferential grooves for the teeth of the first and second rolls and cooperating with the latter to effect a second stage of crushing for material issuing from the first stage, said third roll being spaced closer to the first and second rolls than the spacing of the latter.

5. In a clinker grinder for combustion apparatus, first and second toothed rolls rotatable toward each other and defining a first crushing stage, a third roll spaced closer to the respective first and second rolls than the spacing of the latter and cooperating therewith to define a second crushing stage for material issuing from the first stage, said third roll embodying a shaft with a plurality of rings disposed thereon in side-by-side relation and the rings having lateral spacing means so as to provide circumferential grooves for the teeth of the first and second rolls, and means for supporting the shaft and providing for adjustment thereof so as to vary the distance between the third roll and the respective first and second rolls.

6. In a clinker grinder for combustion apparatus, first and second toothed crusher rolls rotatable toward each other, mechanism for imparting intermittent rotary motion alternately to the first and second rolls, said first and second rolls cooperating to provide a first stage of crushing of material passing therebetween, a third crusher roll spaced closer to the first and second rolls, respectively, than the spacing of the latter, and means providing for rotation of the third roll in either direction so that it may cooperate with the rotating first or second roll to rotate in a proper direction to provide a second crushing stage for material issuing from the first stage, said third roll having circumferential grooves for the teeth of the first and second rolls.
7. In a clinker grinder for combustion appa-

ratus, first and second toothed crusher rolls rotatable toward each other, mechanism for imparting intermittent rotary motion alternately to the first and second rolls, said first and second rolls cooperating to provide a first stage of crushing of material passing therebetween, a third crusher roll spaced closer to the first and second rolls, respectively, than the spacing of the latter, and means operated by said mechanism for securing concurrent and opposite rotation of the third roll and the first or second roll to provide a second crushing stage for material issuing from the first stage, said third roll having circumferential grooves for the teeth of the first and second rolls.
